[57] CLAIM

The ornamental design for a water fill spout, as shown and described.

DESCRIPTION

FIG. 1 is a perspective view of a water fill spout showing our new design;

FIG. 2 is a side elevational view thereof;

FIG. 3 is a top plan view thereof;

FIG. 4 is a front elevational view thereof; and,

FIG. 5 is a rear elevational view thereof.

The broken line representation of water being discharged from the spout in FIG. 1 is for purposes of illustration only and forms no part of the claimed design.

FIG. 1.

FIG. 2

FIG. 3

FIG. 4

FIG. 5
